ALFRED A. DENNIS, OF GRAND RAPIDS, MICHIGAN

VENEER JOINING MACHINE

Application filed February 10, 1930. Serial No. 427,407.

This invention relates to a veneer joining machine. It is common practice in preparing veneers in order that a sufficient length and width thereof may be made to cover a surface, such as a table, desk or the like, to join two or more veneers, which may be of a relatively narrow width, together bringing the side edges of the veneers which are to be joined together into close and intimate contact and gluing the same securely.

Veneers may be of less than $\frac{1}{16}$ of an inch in thickness in many cases, and previously it has been the universal practice to bring the joints together and overlap the same with a tape, so called, which may be a thin continuous strip of paper, $\frac{3}{8}$ to one inch in width, and glue this tape to both veneers at each side of and lengthwise of the joint. The tape, after a veneer has been laid on a bed for a table, desk top or equivalent structure has to be removed by a finishing process, involving the complete removal of the tape by sanding or other equivalent operation, all of which is expensive, while if the veneer is laid with the tape inside, even though the thickness of the tape is but a few thousandths of an inch, it provides a ridge noticeable after the table is finished.

The present invention is directed to a machine for glue connecting the longitudinal edges of veneers located in the same plane without the necessity of using any covering tape over the joint; but at the same time, if it is desired for any reason to provide veneers with which the tape is connected, the machine is available for such use. That is, it is a primary object and purpose of the present invention to provide a veneer joining machine in which the joints may be glued together without the use of tape connecting means, yet the machine may also be used for joining veneers together with tape connecting means associated therewith.

The invention consists of many novel organizations and constructions and arrangements of elements and parts for effectively attaining veneer joining, all of which may be fully understood from a reference to the following description, taken in connection with the accompanying drawings, in which,

Fig. 1 is an end elevation of the veneer joining machine of my invention.

Fig. 2 is a fragmentary enlarged vertical section substantially on the plane of line 2—2 of Fig. 4.

Fig. 3 is a similar fragmentary vertical section substantially on the plane of line 3—3 of Fig. 4.

Fig. 4 is a longitudinal vertical section substantially on the plane of line 4—4 of Fig. 1.

Fig. 5 is a fragmentary plan view of the under conveying mechanism of the machine, the mechanism for carrying the upper belts being removed and the table over which the veneers are fed shown in dotted outline, and

Fig. 6 is a fragmentary plan view of the feed portion of the machine.

Like reference characters refer to like parts in the different figures of the drawings.

In the construction, a main supporting casting 1 is used at the upper end of which an overhanging horizontal arm 2 is extended in a forward direction, below which is a second forwardly extending arm 3 supporting a horizontal feed table 4 over which the veneers which are to be joined together are fed.

At the front end of the upper overhanging arm 2 a vertically positioned plate 6 is permanently secured on which a housing 7 is mounted for vertical movements through guides 8 at the ends of the plate 6 and cooperating guides 9 on the rear side of the housing. A pair of rollers 10 with an intermediate continuous groove 11 between them is mounted at each end of and within the housing on suitable cross shafts and around the same a pair of endless belts 12 are placed the inner edges of which are spaced apart substantially the distance of the width of the groove 11. Thus an air space is formed, and, as will later be referred to, the glued edges of the veneers lie immediately below this air space and hence no smearing of any excess glue is had. The pair of rollers 10 may have the groove provided by an interposed disk of less diameter than the rollers whereby, in a certain use of the machine as later described, the disk at 11 may be removed and the rollers brought together or the rollers with the grooves around them may

be formed as a solid integral member and for operation of the machine where the groove is not desirable or necessary in the rollers such grooved rollers may be replaced by solid 5 rollers without grooves therein.

Between the rollers mounted at each end of the housing and within the lower part of said housing an elongated hollow enclosed heating member 13 is disposed, the width of 10 which is equal to the combined widths of the two belts 12 and the space between them, as shown in Fig. 3. Posts 14, spaced apart, extend upwardly from the upper side of the member 13, passing through lugs 15 which 15 project forwardly from the rear side of the housing 7. Coiled springs 16 are disposed around the posts between the housing and the lugs 15 and nuts 17 thread onto the upper ends of the posts above said supporting lugs. 20 At the front end of the housing a vertical slotted bar 18, provided at its lower end with a horizontal inwardly extending shoe 19 having an upwardly curved forward end, is adjustably mounted by means of a set screw 20 25 which passes through the slot of the bar 18 and threads into the front end of the housing 7.

The housing 7 and the mechanism carried thereby is adapted to be raised above its normal operative position. For this purpose two arms 21 having rounded or cylindrical lower ends 22 are pivotally mounted on pins 23 which in turn are carried by suitable bosses 23a (see Fig. 6) projecting from the 30 plate 6. The upper ends of the arms 21 are connected by a connecting rod 24. A bearing plate 25 is secured to the upper edge of the back of the housing 7 over the parts 22 which are located in recesses in the back 35 plate of the housing and underneath the bearing plate 25 so that if the rod 24 is grasped and pulled to the right, in Fig. 4, the housing is lifted. An arc shaped bracket 26 is secured to the fixed plate 6 and has an 40 arcuate slot 27 therein whereby a stop member 28 may be adjustably mounted at any desired position in the length of the slot 27, against which one of the arms 21 normally bears when the housing with its attached 45 mechanism is free to move downward by gravity, stopping when the arm 21 engages against the stop 28. The distance that the lower run of the belts 12 is located above the upper side of the table 4 is determined by the 50 position of the stop 28 and for different thicknesses of veneers which may be joined on the machine the block 28 will be adjusted to different positions as is evident.

Attached to the underside of the table 4 55 in front of the front end of the housing 7 is a glue holding receptacle 29 around which is a jacket 30 for the entrance of steam or hot water thereto to maintain the glue in a hot fluid condition. A flat disk plate 31 having a large number of small perforations

therein is mounted on a horizontal shaft 32 between the sides of the glue receptacle 29 and extends upwardly through a slot in the table 4 directly in front of the shoe 19 and in a vertical plane coincident with the vertical 70 plane of the grooves 11 in the rollers 10. This plate, when it is immersed in the glue, has the openings therein filled with glue so that when the plate is turned to carry said openings above the level of the glue, some 75 glue is retained and carried in said openings and spreads over the face of the plate between the openings.

At the underside of the table 4 directly below the slot 5 therein a horizontal combined supporting bar and steam receptacle 33 is disposed being permanently secured at the front end of the arm 3 directly below the first hollow steam receiving member 13. At both its front and rear sides it is provided with longitudinally disposed horizontal projections 34 extending nearly the full length of the member 33, through each of which at closely spaced apart points vertical rods 35 pass, the upper ends of which are 80 forked and carry idler rollers 36. The rods with attached rollers are normally pressed upwardly by coiled springs 37, as shown in Fig. 3, until stopped by the nuts 38, on the lower ends of said rods, engaging against 85 the undersides of the projections 34. These rollers extend into the slots 5 in the table 4 and will bear against the underside of veneers passing over the table.

The front end of the member 33 is continued in a downward and widened extension 39 while the rear end is continued downwardly and to the rear in extensions 40. These extensions are divided to provide 90 spaced apart ears between which the rollers 41, with a groove 42 between them, are mounted on suitable shafts. A pair of endless belts 43 passes around the rollers and the upper run of said belts passes over the 95 upper side of the heating member 33. It will be seen that the groove 42 is directly below the previously mentioned groove 11 and serves the same purpose. Thus smearing and progressive accumulation of the glue is absolutely prevented as the excess of glue is merely carried along on the veneers and leaves the machine therewith. Obviously, such is a very material advantage as will be appreciated by those skilled in this art.

Two beveled rollers 44, one at each side of the divided front extension 39, are mounted to turn on axes located at an acute angle to the vertical and are carried by slides at 45 on the opposite sides of the ears at 39, being normally pressed upward by the springs 46, as shown in Fig. 2, to bear against the undersides of veneers fed into the machine, and cause the veneers to be moved at their adjacent edges toward each other and pressed into close intimate contact with each other.

An electric motor 47 is carried on a suitable table support at the back of the main supporting casing 1 and through a suitable driving variable speed mechanism, indicated 5 at 48 the details of which form no part of the present invention, and through gearing 49, an upper shaft 50 is driven which serves to drive the shaft 51 on which the rear wheels 10 are mounted through an interposed connecting shaft 52 and universal joints 53 as shown in Fig. 1. Likewise a shaft 54 is driven from said gearing at the same speed and it is on the end of this shaft that the rear rollers 41 of the lower pairs of rollers 15 are mounted so that the belts 12 and 43 move with equal speed and will carry veneers 54 fed into the machine at the front continuously to the rear.

Two veneers one at each side of the disk 20 31 are fed into the machine having their adjacent edges bearing against opposite sides of the disk as they pass the same so that the edges of the veneers are coated with glue. The veneers are pushed to the belts 12 and 43 25 and to the beveled rollers 44 the movement of the belts drawing the veneers through the machine. By reason of their engagement with the beveled rollers 44 they are moved laterally toward each other whereby the 30 glued edges come into contact with each other directly below the groove 11 and above the groove 42 in the front rollers. The belts carry the veneers at relatively slow speed through the machine and under the steam 35 heating member 13 and over the steam heating member 33. Any excess of glue will squeeze out at the joints between the veneers and lie in the spaces between the belts 43 and 12 and will not engage with the rollers or 40 belts to stick on the same.

The heating members 13 and 33 through which a heating fluid such as steam, may be passed, serve to quickly dry the glue and cause its setting so that by the time the veneers pass from the rollers and belts they 45 are firmly joined together and in effect are one integral flat veneer. The same machine with solid rollers and single flat belts around them, or the two belts brought together at 50 their edges, may be used to feed veneers and a tape to cover the joint, the tape riding on top of the veneers and at both sides of the joint and being glued thereto in the usual manner except that the glue is more quickly 55 set by reason of the heat applied.

It is of course to be understood that instead of or in addition to the beveled rollers 44 for bringing the glued edges of the veneers in contact, the belts may be disposed at an 60 angle to each other so as to bring the veneers in contact. Both methods of bringing the veneers together are well known and either may be used. The construction described is very practical and serviceable and with it 65 the joining of veneers at their edges may be

very quickly and easily performed without the use of the undesirable tape method heretofore universally used. The invention is defined in the appended claims and is to be considered comprehensive of all forms of structure coming within their scope.

I claim:

1. A machine of the class described comprising, a horizontal table having an elongated slot therein, two endless belts mounted on spaced apart rollers below said table and having the upper runs thereof located in said slot in the table so as to be flush with the upper side of the table, said belts being spaced a short distance apart, heating means extending between the rollers under the upper runs of said belts, a second pair of endless belts mounted over the table on spaced apart rollers with their lower runs spaced a short distance above the upper runs of the lower belt, said pair of upper belts being lengthwise spaced a short distance apart, heating means above the lower runs of the upper belts and extending between the rollers on which they are mounted, means located on the table in front of the belts for simultaneously gluing adjacent edges of two veneers manually moved over the table to said belts, said veneers having their glued edges contacting when engaged and carried by said belt over the table, the joint formed by said glued edges being in a vertical plane passing through the spaces between said upper and lower pairs of belts.

2. A construction containing the elements in combination defined in claim 1 combined with means for adjustably controlling the distance that the lower runs of the upper belts are separated from the upper runs of the lower belts whereby different thicknesses of veneers may be carried by said belts over the table.

3. A construction containing the elements in combination defined in claim 1, each of said upper belts being of greater width than the lower belts, and pressure means located alongside of and at the outer edges of said lower belts and adapted to exert upward pressure against veneers fed over the table so as to press the same snugly against said upper belts.

4. A construction containing the elements in combination defined in claim 1, said rollers carrying the upper belts, and likewise, said rollers carrying the lower belts, each having an annular groove at its outer side, said groove being disposed at the inner edges of the belts and being in width substantially equal to the distance that the belts are spaced apart.

5. In a machine of the class described, a horizontal table having a longitudinal slotted opening therein, an endless belt conveyor mounted below the table having the upper run of the belt in said slotted opening and

with its upper side flush with the upper side of the table, a horizontal housing mounted for vertical adjustment above the table, an endless belt within said housing having its 5 lower run spaced a short distance from the upper run of the lower belt, manually operable means for raising said housing and the mechanism carried thereby, and adjustable stop means adapted to be secured in a 10 fixed position in the path of movement of said manually operable means for determining the lowermost position of said housing and the belt carried thereby.

6. A machine of the class described comprising, a support, spaced apart rollers thereon, two endless belts mounted on said rollers and having the upper runs level with each other, a second pair of endless belts mounted on spaced apart rollers with their 20 lower runs spaced a short distance above the upper runs of the lower belt, said first mentioned belts being narrower than the second pair of belts, and pressure means located alongside of and at the outer edges of said 25 lower belts and adapted to exert upward pressure against the lower runs of the upper belts.

7. In a machine of the class described, a horizontal table, endless means mounted on 30 and lengthwise of the table for grasping and carrying two veneers over the table with adjacent edges in contact with each other, said endless means being laterally spaced from the meeting edge of the veneers, and 35 heating means disposed above and below the path of movement of the contacting edge portions of the veneers, one of said heating means being slightly spaced vertically from the meeting edge of the veneers whereby an air 40 space is had therebetween.

8. A machine comprising the elements in combination as set forth in claim 7 and having the heating means spaced from the veneers whereby an air space is had both below and above the meeting edge of the 45 veneers.

9. A glue applying apparatus comprising a table having a slotted opening therein, said table being adapted to receive sheets of 50 veneer thereupon, means to apply glue to one edge of each sheet of veneer, means to maintain the edges having glue thereon snugly adjacent each other and to move the sheets of veneer so that said common edge passes 55 over the slotted opening in the table, said last mentioned means being slightly spaced from the common edge of the sheets of veneer and heating means above said common edge but slightly spaced therefrom whereby an 60 air space is had therebetween.

10. A veneer joining machine comprising a support, two endless belts mounted on spaced apart rollers below said support, means adapted to be cooperatively associated 65 with the belts whereby pieces of veneer may

be moved by said belts and heating means below the upper runs of the belts whereby heat will act upon the pieces of veneer between the spaced belts, said heating means being spaced from the veneer whereby an air space is had therebetween.

11. In a machine of the class described, a support, means mounted on said support for grasping and carrying two veneers over the support with adjacent edges in contact with each other, said means being in contact with the veneers at points spaced from the juncture of the said two veneers, and heating means spaced a short distance from said juncture whereby no contact is had therewith for the purpose described.

In testimony whereof I affix my signature.
ALFRED A. DENNIS.
